(57) **CLAIM**

The ornamental design for an athletic cap liner, as shown and described.

DESCRIPTION

FIG. 1 is a perspective view of the cap liner viewed from an upper left, front position;

FIG. 2 is a perspective view of the cap liner viewed from a lower left, rear position;

FIG. 3 is a top view of the cap liner;

FIG. 4 is a left side elevational view of the cap liner;

FIG. 5 is a front elevational view of the cap liner;

FIG. 6 is a rear elevational view of the cap liner;

FIG. 7 is a bottom view of the cap liner; and,

FIG. 8 is a side elevational view of the cap liner showing it in the environment of use.

The broken line portion shown in FIG. 8 is for illustrative purposes only and forms no part of the claimed design.
